UNITED STATES PATENT OFFICE

WILLIAM BOWDEN, GEORGE L. MILLER, AND JOHN MIKULASEK, OF NEWTON, IOWA,
ASSIGNORS TO THE MAYTAG COMPANY, OF NEWTON, IOWA, A CORPORATION OF
DELAWARE

WRINGER

Application filed June 8, 1929. Serial No. 369,294.

The present invention relates to wringers, such as are used in connection with power washing machines.

Among the objects of the invention is to provide a novel wringer frame provided with guiding webs for guiding articles or clothes between the rolls in the frame and to guide them away as they pass through the rolls.

10 Another object of the invention is to provide a novel wringer frame having a longitudinal opening therein below the rolls for directing water dripping from the rolls to means associated with the opening which 15 divert the water to either side of the wringer.

20 A further object of the invention is to provide a novel means for diverting water which drips from the rolls during the wringing operation back into the tub or other container to which the wringer may be attached. The invention comprehends the idea of mounting this diverting means or drain plate in the frame of the wringer so that clothes passing through the rolls 25 thereof will not tip or tilt the plate to divert the water from the rolls to the wrong side of the wringer and away from the tub or other container.

30 Another object of the invention is to provide means for automatic tilting or tipping the drain plate or diverting means to direct the water from the rolls back into the tub or other container to which the wringer may be attached.

35 As a further object of the invention, means are provided for preventing vibration of the drain plate when the wringer is operating.

40 In a specific embodiment illustrative of the invention, the lower part of the frame is provided with web or skirt portions on both sides of the frame, sloping downwardly and away from the lower wringer rolls, and web or skirt portions sloping downwardly and toward the lower wringer roll and terminating in spaced relation to each other to form an opening directly below the wringer roll. The longitudinal skirt or web 45 portions terminate to form ridges at their upper portions at approximately the longi-

tudinal axis of the bottom roll and are spaced therefrom. The ridge formed by these skirt or web portions serve as guides for the clothes or objects passing through and out between the rolls. They are spaced from 55 the lower rolls sufficiently far to be of use as guides and also prevent the clothes as they pass through the rolls from becoming entangled with the rolls or other mechanisms associated with the wringer. These skirt or 60 web portions also form a hopper with a longitudinal opening which directs water dripping from the rolls to means below. The skirt or web portions are of further importance inasmuch as they provide a housing 65 for a drain plate pivotally mounted in the ends of the frame and which is directly below the longitudinal opening in the hopper. This housing completely encloses the drain plate, which is automatically tipped or tilted to either side of the wringer dependent upon the direction of rotation of the rolls, and prevents the clothes passing through the wringer from becoming lodged thereon and tipping or tilting it in a wrong direction. 70

75 The drain plate or diverting means is provided with an upstanding arm which passes through the longitudinal opening, the end of which engages an arm of a dog or cam frictionally mounted on one end of the lower roll. The arm of the dog or cam on the lower roll shaft bears against the arm of the tiltable drain plate or diverting means to tip or tilt the drain plate in either of two directions depending upon the direction of 80 rotation of the roll.

85 A further object of the invention is to provide a novel wringer frame in which the lower roll is removably mounted. In the specific embodiment selected to illustrate the 90 invention, one end of the frame is provided with an aperture through which a coupling socket from a gear head projects into the frame. The other end of the frame is provided with a cradle-shaped portion. The lower roll is provided with a shaft, one end of which is adapted to be inserted into the coupling socket and the other end is provided with a bearing adapted to rest on the cradle-shaped portion. The coupling socket 95 100

is driven from a source of power through suitable gearing in the gear head which in turn drives the lower shaft.

- The invention has for a further object, 5 the provision of a novel means for mounting the upper wringer roll, and novel means for holding it in operative position with the lower roll. In an illustrative embodiment of the invention, a pivotal section is provided for the top of the frame, such section having ear or cross members pivotally connected at the ends of the frame and which are provided with bearing units for journaling the ends of the shaft of the upper roll. 10 15 The upper roll is frictionally driven by the lower roll and may be swung out of its normal operative position for cleaning or for repairing the wringer mechanism. In its normal operative position, means are provided for holding the upper roll in such position.

The invention also comprehends other objects, advantages, capabilities and features which will later appear, and are inherently possessed thereby.

Referring to the drawings:

Fig. 1 is a view in side elevation of an embodiment selected to disclose the invention, with parts broken away to show the construction of the lower portion of the frame and drain plate.

Fig. 2 is a bottom plan view of the embodiment selected to illustrate the invention showing in detail the drain plate and means for preventing vibration of the same during operation of the wringer.

Fig. 3 is a top plan view of the embodiment shown in Fig. 1 and showing the top section of the frame released and turned over to expose the parts beneath.

Fig. 4 is a vertical cross sectional view taken in the plane represented by line 4-4 of Fig. 1 and showing in dotted lines the top section of the frame in its turned-back position.

Fig. 5 is a vertical cross sectional view taken in the plane represented by line 5-5 of Fig. 1, showing the construction of the drain plate and its relation to the opening beneath the lower roll.

Fig. 6 is a top plan view of the end of the frame to which the gear head is connected with the lower roll, the top section of the frame being removed to show the position of the drain plate arm extending up through the opening in the lower part of the frame.

Referring now more in detail to the drawings, the embodiment selected to illustrate the invention, comprises a wringer frame 1, provided with standards or hollow upright end members 2 at one end and 3 at the other end. A gear-head casing 4 enclosing suitable gearing and driven from a source of power (not disclosed) is provided with flanges 5 having bolt holes as at 6 which are adapted

to register with holes as at 7 in the frame 1, and the casing is connected to the frame and held in position by bolts 8. Enclosed within the casing and meshing with the gearing in the gear casing 4 is a projecting socket coupling 9 adapted to project through an aperture 10 in the end of the frame and into the space between the standards 2 of the frame 1. A wringer roll 11 having a resilient rubber surface is provided and is mounted on a shaft 12 having an extending portion 13, the end of which is hexagonal shape to form a torque 14 which fits into and couples with the socket coupling 9 and is driven thereby. Mounted upon the other end of the shaft 12 is a bearing casing 15 in which are secured bearings (not shown) surrounding the end of the shaft. The bearing casing 15 is adapted to seat and rest upon the lower portion 16 of a cradle-shaped depression 17 formed between the standards or upright end members 3 at the one end of the frame 1. This roll 11 may be removed from the frame 1 by lifting the end resting in the cradle-shaped depression upwardly and removing the extended portion of the shaft with the torque 14 from the socket coupling 9.

At the lower portion of the frame 1 is provided skirts or webs 18 and 19 extending longitudinally on both sides of the frame 1, and intersecting the standards 2 and 3 to form a filleted guide surface as at 20 at both ends of the frame. The webs 19 are spaced from the roll 11, the intersection of which with the skirts or webs 18 form the guide ridges 21 at approximately the height of the longitudinal center line or axis of the roll 11. The webs or skirts 18 between the standards extend downwardly and away from the ridges 21 to form guiding surfaces for clothes or other articles passing into and through the wringer, while the webs or skirts 19 extend downwardly and inwardly from the ridges 21, the termination of the edges of which form an opening 22 extending longitudinally beneath the roll 11 from the lip portion 22^a which extends downwardly from the cradle-shaped portion 17 between the standards 3 at one end of the frame, to a somewhat similar lip portion 22^b extending downwardly from a recess portion 23 at the other end of the frame 1 and between the standards 2.

The downwardly and outwardly sloping webs 18 are so positioned relative to the wringer rolls that they serve as hand rests for the operator as clothes or the like are being fed into and through the rolls as well as to serve as hand guards to prevent the hand or fingers of the operator from coming into contact with the mechanism of the wringer.

A drain plate 24 tiltably mounted by trun-

nions 25 and 26 bearing in the ends of the frame 1 is provided, and extends coextensively with the longitudinal opening 22 in the hopper formed by the webs 19 and is 5 positioned immediately below the same. This drain plate is housed in by the webs 18 and 19 and is provided at one end with an upstanding arm 27 which extends upwardly and through the opening 22.

10 A spring 28 encircling the trunnion 26 and having one end bearing against a wall 29 of the drain plate and the other end bearing against a pin 30 projecting through the slideable trunnion 26, provides means for holding 15 the slideable trunnion 26 in its normal extended position and to exert pressure upon the drain plate 24 and to hold the same firmly in adjusted position to prevent vibration during the operation of the wringer, and also 20 to permit the drain plate to be easily removed from its bearing in the frame 1 for repairing the same or other mechanisms of the wringer.

A split cam or dog 31 is mounted upon the 25 extended portion 13 of the shaft 12, being held in frictional engagement with the shaft 12 by a ring 32 seating in an annular groove 33 around the split cam or dog. One of the split members of the cam or dog 30 31 is provided with an extending arm 34 which engages or bears against the arm 27 of the drain plate 24 when the same is in its normal adjusted operative positions. The cam or dog 31 normally bears against 35 the arm 27 to keep the drain plate 24 in a tilted position so that the water dripping from the wringing operation through the opening 22 is diverted or directed back into the tub or other container to which the 40 wringer may be connected. If the lower roll is rotated in a reverse direction, the cam or dog 31 will be swung around because of its frictional mounting on the shaft 12 to bear or engage the arm 27 on the other side to tilt 45 the drain plate 24 in a reverse direction and thereby direct the water to the other side of the wringer.

Pivoted to the standards or upright end members 2 and 3 of the frame is a pair of 50 cross members or ears 35 and 36 to which is pivoted a cap plate 37, having a pivotal member or members 38 flattened as shown in Fig. 3 and as indicated by the line 39 in Fig. 4. It will be seen that when the cap 55 plate 37 is in the position shown in Fig. 4, the member or members 38 will engage hooks or latch members 40 passing up through the standards or upright end members opposite- 60 ly located to those standards or upright mem bers to which the cross members or ears 35 and 36 are pivotally connected. The hooks or latch members 40 extend down through the top of the standard and into the hollow compartment below, and are provided with 65 a nut 41 engaging the threaded end of the

hook and between which and the top plate of the standard is a spring 42 for holding the hook or latch member 40 in engagement with the member 38 of the cap plate 37. The cross members 35 and 36 are provided with extending portions 43 which provide a seating means for bearing casings 46 adapted to hold bearings and in which are journaled the ends of a shaft 44 upon which is mounted the roll 45.

When the cap plate 37 is in the position as shown in Fig. 5, the member or members 38 will engage the hook or latch member 40 to hold the cross members or ears 35 and 36 down in the position intended for wringing and the upper roll 45 will frictionally contact with the lower roll 11 and be driven thereby, but that when the cap plate 37 is turned or opened to the position shown in Fig. 3 or by dotted lines as in Fig. 4, the pivots 38 will be released from the hooks or latch members so that the cap plate, cross members and upper wringer roll may be turned on the pivots connecting the cross members or ears with the standards or upright members of the frame.

This structure makes it very easy to release the tension on the rolls, in the event that the hand should get caught between the rolls, or clothes get bunched in going through the wringer. It also makes it easy to open up the wringer for the purpose of taking out the wringer rolls. The bearing casings 46, in which are positioned bearings about the journaled end of the shaft 44, are removably mounted upon the shaft but are retained on the shaft when the roll 45 is removed from the extending portions 43. Whenever it becomes necessary to remove the upper roll because of injury or because of the wear, a new wringer roll with its bearing casings positioned on the ends thereof, may be easily mounted in the extending portion 43 of the ears or cross members.

While we have herein described and upon the drawings shown an illustrative embodiment of the invention, it is to be understood that the invention is not limited thereto but comprehends other constructions, details, arrangements of parts and features without departing from the spirit thereof.

Having thus disclosed the invention,

We claim:

1. In a wringer comprising a frame and upper and lower wringer rolls mounted in said frame, said frame provided with a hopper associated with said lower roll, a drip plate rotatably journaled in said frame and below said hopper, and means controlled by the movement of said rolls for tilting said drip plate to divert water to either side of said wringer as it drips through said hopper.
2. In a wringer comprising a frame and upper and lower wringer rolls mounted on shafts, said shafts journaled in the frame,

said frame provided with a hopper associated with said lower roll, a drip plate in said frame and below said hopper, and means on said lower shaft for automatically tilting said plate to either side of said wringer as said rolls are being rotated in a forward or reverse direction.

3. In a wringer comprising a frame and upper and lower wringer rolls mounted on 19 shafts, said shafts journaled in said frame, a drip plate tiltably mounted in the lower portion of said frame and provided with an arm, said frame provided with a longitudinal hopper associated with said lower roll and spaced therefrom and adapted for guiding articles 25 through said rolls and to house said plate, means frictionally engaging said lower shaft and adapted to bear against said arm on said plate for holding the plate in a tilted position.

4. In a wringer comprising a frame, upper and lower wringer rolls removably mounted in said frame, said frame provided with a longitudinal hopper at its lower portion, said 25 hopper surrounding a portion of said lower roll and spaced therefrom, and means housed within said hopper for diverting water dropping through said hopper to either side of said wringer.

5. In a wringer provided with rolls, a frame having a longitudinal opening therein at the lower portion and associated with the lower roll, a drain plate tiltably mounted in said frame below said opening, said wringer rolls being mounted on said frame and provided with shafts, a cam driving member having a frictional mounting on one of said roll shafts, said drain plate having an arm engaging said driving member whereby said drain plate is tilted on rotation of said wringer roll shaft.

6. In a wringer comprising a frame, a drive head provided with a coupling in association with said frame at one end thereof, the other end of said frame provided with a cradle-shaped portion, a roll mounted on a shaft, one end of said shaft journaled in and driven by said coupling, the other end of said shaft being provided with a bearing adapted to rest upon said cradle-shaped portion, and a roll in surface contact with said first roll, said frame provided with a longitudinal opening, and a drain plate below said opening adapted to divert water dropping through said opening to either side of said wringer, the operation of said plate being controlled by the operation of one of said rolls.

7. In a wringer comprising a frame, a 69 drive-head provided with a coupling in association with said frame at one end thereof, the other end of said frame provided with a cradle-shaped portion, a roll mounted on a shaft, one end of said shaft journaled in and 75 driven by said coupling, the other end of said

shaft being provided with a bearing adapted to rest upon said cradle-shaped portion, and a roll in surface contact with said first roll, said frame provided with a longitudinal opening, a drain plate below said opening and tiltably mounted in said frame and provided with an arm, a cam member frictionally mounted on one end of said roll shaft and provided with an extending arm, said extending arm adapted to bear against the arm 75 of said drain plate to tilt the same and divert water passing through said opening to either side of said wringer.

8. In a wringer comprising a frame, a drive-head provided with a coupling in association with said frame at one end thereof, the other end of said frame provided with a cradle-shaped portion, a roll mounted on a shaft, one end of said shaft journaled in and driven by said coupling the 80 other end of said shaft provided with a bearing adapted to rest upon said cradle-shaped portion, a roll in surface contact with said first roll, said frame being provided with a longitudinal opening, a drain plate below 85 said opening and tiltably mounted in said frame and provided with an arm, a cam member frictionally mounted on one end of said roll shaft and provided with an extending arm, said extending arm adapted to bear against the arm of said drain plate to tilt the same and divert water passing through said opening to either side of said wringer, and means attached to said drain plate to prevent vibration of said plate when 90 the wringer is operated.

9. In a wringer, a frame therefor, upper and lower wringer rolls, said frame having a housing below said rolls, said housing being provided with inwardly extending skirt portions terminating in an opening beneath the lower roll, and means enclosed within said housing controlled by one of said rolls for diverting water passing downwardly through 100 said opening to either side of said wringer.

10. In a wringer, a frame therefor, upper and lower wringer rolls, said frame having a housing below said rolls, said housing having a hopper surrounding a portion of said 115 lower roll and spaced therefrom, and a tiltable drain plate below said hopper and enclosed within said housing for diverting water to either side of said wringer, the tilting thereof being controlled by the rotation of 120 said rolls.

11. In a wringer, upper and lower rolls therefor, a frame for journalling said lower roll, said frame having a housing provided with an opening below said lower roll, and a drain plate below said opening and within said housing for diverting water passing through said opening to either side of said wringer, said drain plate being tilted in op-

posite directions by the operation of one of
said rolls.

In witness whereof, we hereunto subscribe
our names to this specification.
